DRYING APPARATUS HAVING OPERATION
SEQUENCE CONTROLHarold F. Gorsuch, Mansfield, Ohio, assignor to
Westinghouse Electric Corporation, East Pitts-
burgh, Pa., a corporation of Pennsylvania

Application December 29, 1945, Serial No. 638,353

7 Claims. (Cl. 34—45)

1

My invention relates to drying apparatus, more particularly to apparatus for drying fabrics or the like, and has for an object to provide improved apparatus of this kind.

A further object of the invention is to utilize the heat remaining in the drying chamber of a drier subsequent to the deenergization of the heaters for completing the drying operation and, concomitantly, progressively cooling the material being dried.

A still further object of the invention is to provide an improved control for a drier which may be manually operated to initiate a drying operation and which effects a predetermined sequence of drying steps automatically, at the conclusion of which the drier is rendered inactive.

These and other objects are effected by my invention as will be apparent from the following description and claims taken in connection with the accompanying drawings, forming a part of this application, in which:

Fig. 1 is a vertical section taken along the line I—I of Fig. 2 and showing a form of clothes drier controlled in accordance with my invention;

Fig. 2 is a sectional view taken along the line II—II of Fig. 1;

Fig. 3 is a diagram of the electrical connections of the control apparatus used to control the drier shown in Figs. 1 and 2;

Fig. 4 is a view similar to Fig. 1 and showing a second embodiment of the invention; and

Fig. 5 is a diagram of the electrical connections for the drier shown in Fig. 4.

Reference will now be had to Figs. 1 to 3, inclusive, wherein I have elected to show my invention applied to a clothes drier of the domestic type and provided with a housing structure 10, the front wall 11 of which is provided with an access opening 12 and a suitable hinged door 13 for closing the opening. The housing 10 also includes a back wall 14 for suitably supporting a bearing 15 in which a shaft 16 is journaled. The latter supports a basket 17 for containing the clothes to be dried, which basket 17 includes a perforate side wall 18, a number of the perforations being shown at 19. The basket 17 is provided with a plurality of inwardly-extending vanes 21 which function to tumble the clothes during rotation of the basket. The front end of the basket 17 is provided with an access opening 22 which registers with the access opening 12 of the housing.

A generally cylindrical baffle 23 is disposed

2

within the housing 10 and encloses a drying chamber 24 within which the basket rotates. An upper portion of the baffle 23 is recessed to provide a cove 25 for housing an electric heating element, of any well-understood construction and indicated at 26. An air inlet opening 27 is formed in the baffle 23 and a relatively large throat 28 is provided at the bottom of the baffle for the discharge of the heated, humid air from the chamber 24. A plurality of openings 29 may be provided in the recessed portion of the baffle 23 for the ingress of air to the cove 25 and the heating chamber 24. Admission of air from the ambient atmosphere to the housing 10 is afforded by a plurality of louvred openings 31 arranged in one of the walls of the housing 10, such as, for example, the front wall 11.

The basket 17 and its shaft 16 are rotated at a speed of, for example, 50 R. P. M. by means of a sheave 32 fixed to the shaft 16 and belted, as shown at 33, to a pulley 34 driven by an electric motor 35. The motor 35 also drives a blower 36 having a discharge port 37 extending through the housing 10 for the delivery of humid air to the ambient atmosphere. The inlet eye of the blower 36 is shown at 38 and communicates with a chamber 39 formed in the bottom of the housing 10 and communicating with the throat 28. Preferably a lint trap 41 formed, for example, of a flat sheet of screen cloth, is disposed between the throat 28 and chamber 39 for the gathering of lint which may accumulate during the tumbling of fabrics in the basket. Preferably the lint trap 41 is removable, by means of a handle 42, through a suitable opening in the front wall 11 of the casing for the periodic cleaning of the lint trap.

As described hereinafter, the operation of the heater 26 and the motor 35 is controlled by a timer, generally indicated at 44 and carried by an upper portion of the housing 10; the timer 44 having a manually-operated knob 55 for initiating operation of the timer and accessible at the front of the cabinet. The timer 44 will be described more in detail hereinafter. Energization of the heater 26 is also controlled by a thermostatic switch, generally indicated at 40 and carried by the baffle 23 in a position where it will reflect the temperature of the atmosphere within the drying chamber 24.

According to my invention, the timer 44 conditions the heater 26 for energization accompanied by operation of the motor 35 for a predetermined period of operation of the timer, at the conclusion of which period the heater 26 is

rendered inactive. The motor 35, however, continues to operate for a second predetermined period of operation of the timer to continue the tumbling of the fabrics and the circulation of air through the chamber 24. It is during the continued operation of the motor 35 that the heat remaining in the chamber 24 subsequent to the deenergization of the heaters 26 is utilized to complete the drying operation, and a concomitant of this operation is that the clothes are cooled to a temperature at which they may be comfortably handled as they are removed from the basket.

Reference will now be had particularly to Fig. 3 for a diagrammatic representation of the timer and the electrical circuits between the various electrical translating devices, referred to heretofore. The timer 44 includes three switches 46, 47 and 48, all of which are biased to their open position and actuated to their closed position by respective cams 49, 50 and 51. The cams 49 to 51, inclusive, are fixed to a shaft 52 which is rotated at a relatively slow speed by means of a speed-reducing mechanism 53 driven by a timing motor 54. The latter may be of the synchronous type usually employed for driving clocks. The shaft 52 is provided with a knob 55 which may be manually actuated to advance the cams 49 to 51, inclusive, when initiating operation of the timer. A slip clutch 56 is employed to permit rotation of the shaft 52 relative the speed-reducing mechanism 53 during a manual adjustment of the cams, and which also functions to drive the shaft 52 during operation of the timer motor 54. Regardless of whether the shaft 52 is manually actuated or driven by the motor 54, rotation is clockwise as shown by the arrow on the knob 55.

The source of power for the apparatus is defined by line conductors L₁ and L₂ and a conductor N. These three conductors are usually connected to a three-wire, single phase Edison distribution system wherein the potential across the line conductors L₁ and L₂ approximates 230 volts, while the potential from either of the line conductors L₁ and L₂ to the neutral conductor N is approximately 115 volts. As shown, the conductors L₁ and L₂ are respectively connected to one side of each of the switches 46 and 47, and the conductor L₁ is also connected to one side of the switch 48 by means of a conductor 58. The opposite side of the switch 46 is connected, by means of a conductor 59, to one terminal of the heater 26 through a pair of contacts 61 forming a part of the structure of the thermostat 40.

The thermostat 40, which may be of any well-understood construction, includes a heat-actuated member, such as a bimetallic disc 62, which, when the temperature of the atmosphere within the heating chamber 24 is below a predetermined value, bridges the contacts 61 for energizing the heater 26. Conversely, when the temperature of the air within the chamber 24 is above a predetermined value, the bimetallic element 62 snaps to the position shown in dotted lines in Fig. 3, for opening the heater circuit at the contacts 61. In the latter position of the thermostatic element 62, a pair of contacts 63 are bridged for energizing the timer motor 54, further reference to which will be made hereinafter. The opposite terminal of the heater 26 is connected by a conductor 64 to the movable contact of the switch 47.

One terminal of the main motor 35 is directly connected to the neutral conductor N, while the opposite terminal is connected by means of a conductor 65 and the conductor 64 to the switch

47. From this connection, it will be apparent that the motor 35 operates during the period of time that the switch 47 is closed. It will also be apparent that the main heater 26 is conditioned for energization under control of the thermostat during periods when the switch 46 is closed. From the shape of the cams 49 and 50, it will be seen that the switch 47 is closed simultaneously with the closing of the switch 46 and that the switch 10 47 remains closed for a period of time after the switch 46 is opened.

During the heating steps in the drying program, the timer motor is energized during periods when the thermostat 40 is satisfied, or, in other words, when the temperature in the chamber 24 is above the value at which the thermostatic disc 62 snaps to its dotted line position. Conversely, when the thermostat 40 is calling for heat, the timer motor 54 is deenergized. As 15 shown, one terminal of the timer motor 54 is connected by a conductor 66 to one contact 63 of the thermostat 40, the opposite contact 63 being connected to the conductor 59. The opposite terminal of the timer motor 54 is connected by means of a conductor 67 to the neutral conductor N. A switch 68 may be interposed in the conductor 67 for manually rendering the timer motor 54 inactive, the purpose of which will be referred to hereinafter. The conductor 66 is 20 also electrically connected by means of a conductor 69 to the movable contact of the cam-operated switch 48. From this connection, it will be apparent that, when the switch 48 is closed towards the conclusion of the heating step in the cycle, the timer motor 54 will be continuously energized 25 regardless of the position of the thermostat 40.

In operating the drier described heretofore, the operator deposits the wet fabrics in the basket 17 and closes the door 13, after which the timer knob 55 and the cams 49 to 51 are moved angularly from the "off" position of the timer to the "on" position thereof, which movement is sufficient to close the switches 46 and 47. Accordingly, the heater 26 is energized since the thermostat disc 62 is relatively cool and is, therefore, in the position shown wherein the contacts 61 are bridged. The circuit for energizing the heater 26 includes the line conductor L₁, the switch 46, conductor 59, the bridged contacts 61, heater 26, conductor 64, 45 switch 47 and line conductor L₂. The main motor 35 is also energized for tumbling the fabrics and for the circulation of air therethrough by means of a circuit extending from the line conductor L₂ and including the switch 47, conductors 64 and 50 65, main motor 35 and a neutral conductor N. Since the contacts 63 and the switch 48 are open, the timer motor 54 is inactive.

The heat generated by the heater 26 at this time progressively increases the temperature of 55 the drier structure and the fabrics contained therein. During the early stages of this heating step, the rise in temperature within the chamber 24 is relatively slow as a substantial portion of the energy dissipated by the heater 26 is converted to latent heat of vaporization and a relatively small percentage of the energy dissipated by the heater is converted to sensible heat. As the drying progresses, more energy is converted to sensible heat and less to latent heat so that the 60 temperature rise is increased. When the temperature of the chamber 24 is increased to a predetermined high value of, for example, 180° F., the thermostat 40 opens the contacts 61 and closes the contacts 63. Accordingly, the heater 26 is 65 deenergized and operation of the timer is initiated 70 75

since the timer motor 54 is now energized by means of a circuit including line conductor L₁, closed switch 46, conductor 59, the bridged contacts 63, conductor 66, timer motor 54, conductor 67 and the neutral conductor N.

The cams 49 to 51 are now rotated clockwise at a relatively low speed. During this operation of the timer, the temperature within the chamber 24 may drop to a predetermined value of, for example, 160° F., so that the contacts 61 are again bridged for energizing the heater 26 and the contacts 63 are opened, whereupon operation of the timer motor ceases. The heater 26 will be energized and deenergized under control of the thermostat 40 until the timer cams have been advanced sufficiently to open the switch 46 whereupon the heater 26 is deenergized for the remainder of the cycle. At this time, the clothes are substantially dry. Shortly before the opening of the switch 46, the switch 48 is closed to establish a shunt circuit around the contacts 63 for the continuous energization of the timer motor 54. This shunt circuit includes the conductors L₁, 58 and 69. It will be understood that the main motor 35 continues operation after the opening of the switch 46 as its circuit is maintained by the closed switch 47.

During the latter part of the drying cycle or after the heater 26 has been deenergized by the opening of the switch 46, the continued circulation of air through the chamber 24 completes the drying operation. The stored heat is utilized for this purpose, and since there is a continuous flow of relatively cool air from the ambient atmosphere, the drier structure is cooled as the fabrics are being dried. After a predetermined period of continuous operation of the timer 44, the switch 47 is opened by the cam 50, whereupon the main motor 35 is deenergized. Shortly thereafter, the cam 51 opens the switch 48 for de-energizing the timer motor 54. The apparatus is now in the "off" position, as shown, and the dried fabrics may be removed from the basket.

The steps in the drying cycle recited heretofore obtain whether the load to be dried is heavy or light. However, the total duration of the drying cycle will be longer with a heavy load, inasmuch as longer periods of energization of the heater are necessary to vaporize the moisture. Conversely, with a light load the periods of energization of the heater 26 are shorter and the duration of the entire cycle will be relatively short. The wattage of the heater 26, the amount of air translated through the drying chamber 24 and the speed at which the timer motor 54 advances the cams are correlated so that the majority of the loads usually dried in apparatus of this kind will require but a single setting of the control knob 55. If the knob 55 is adjusted to its "on" position, as indicated, without any additional angular movement of the knob, the fabrics will be thoroughly dried when removed from the drier. The operator may, however, in initiating operation of the apparatus, advance the knob 55 beyond its "on" position in order to shorten the time that the switch 46 is closed during the heating cycle. Accordingly, when the cycle is terminated the fabrics are damp in order to provide for immediate ironing. The amount of dampness remaining in the fabrics may be selected by the operator when initiating the cycle by advancing the control knob more or less. In this connection, indicia may be provided on the knob 55 to guide the operator in selecting the

degree of dampness in the fabrics at the conclusion of the cycle.

Occasionally extremely heavy drying loads are encountered such as, for example, when a plurality of heavy throw rugs are to be dried or when the amount of moisture in any load is heavy, and when such conditions prevail, it is desirable that the machine be capable of manual operation. It is for this reason that the switch 68 is provided. In order to operate the machine manually, the timer is advanced to its "on" position, as described, and the switch 68 is moved to its "off" position. Accordingly, the heater 26 is operated under control of the thermostat 40, and since the motor 35 is energized, air is circulated through the drier. However, the opening of the switch 68 prevents operation of the timer motor. When the load is dried, the operator moves the timer to the "off" position or may advance the timer to the position wherein air circulation only is effected and then close the switch 68. Accordingly, the load will be cooled during the operation of the timer to its "off" position. The switch 68 is so constructed that it is retained in its "on" or "off" position after having been moved to either one of these positions.

The drier which I have indicated in Fig. 4 and constituting a second embodiment of the invention is constructed generally along the lines described heretofore, and parts which are common to both are indicated by similar reference numerals. This drier is provided with thermostat, indicated at 71, for controlling energization of the heater 26 and constitutes a safety thermostat which prevents overheating of the air in the chamber 24. The second thermostat 72 reflects the temperature of the discharged air and is preferably located in the chamber 39. As shown in Fig. 5, the thermostat 72 is constructed generally along the lines of the thermostat 40, in that it includes a bimetal element 73 which moves from the position shown in the drawing to its dotted line position, in response to a predetermined temperature of, for example, 180° F. This thermostat 72 is, however, of the high differential type and is adapted to move from its dotted line position to the position shown in the drawing, when the temperature of the air has been depressed to a temperature of, for example, 130° F. The thermostat 71 may be arranged to open its contacts at a temperature of 185° F. and functions as a safety device which in normal operation remains closed.

As shown in Fig. 5, the thermostatic element 73 bridges contacts 74, which indicates that its temperature is below 130° F. When the temperature of the air in the discharge duct attains 180° F., the element 73 moves to its dotted line position, wherein it bridges contacts 75. The element 73 remains in this dotted line position until the temperature has been depressed to 130° F.

The timer structure associated with Fig. 4 is indicated generally by the numeral 76 and includes a pair of cams 77 and 78 which are rotated with the shaft 52 by the timer motor 54 through the reduction gearing 53. As in the first embodiment, the shaft 52 may be moved angularly manually by the knob 55 from an "off" position to an "on" position.

The cam 77 in the "on" position closes a pair of switches 81 and 82 and the cam 78 closes the switch 83. One terminal of the switch 81 is connected to the line conductor L₁ and the other contact of the switch 81 is connected to a ter-

terminal of the heater 26 through the thermostat 71. The other switch 82 has one of its contacts connected directly to the line conductor L₂ and its second contact connected to the opposite terminal of the heater 26 through the contacts 74. One terminal of the timing motor 54 and one terminal of the main motor 35 are electrically connected by a conductor 84 to the stationary contact of the cam-operated switch 83, the movable contact of which is directly connected to the neutral conductor N. The opposite terminal of the timer motor 54 is connected by means of a conductor 85 to the line conductor L₁ through the contacts 75 of the thermostat 72. The opposite terminal of the main motor 35 is connected by means of a conductor 86 to the line conductor L₂.

In initiating operation of the drier shown in Figs. 4 and 5, the timer is advanced to its "on" position after the damp clothes have been deposited in the basket 11. Accordingly, the switches 81, 82 and 83 are closed. Closure of the switches 81 and 82 energizes the heater 26, it being understood at this time that the thermostat 72 is relatively cool or at room temperature. The closure of the switch 83 energizes the main motor 35 which operates, as described heretofore, to tumble the fabrics in the basket and to circulate air through the drying chamber 24. Operation of the heater 26 increases the temperature within the chamber 24, the increase being relatively slow at the beginning of the heating cycle because of the large amount of water to be evaporated. As the drying progresses, the temperature increases rapidly as described heretofore. During this drying operation, the timer motor 54 is inactive. When the temperature of the air in the discharge duct attains 180° F., indicating the fabrics are substantially dry, the thermostatic element 73 moves to its dotted line position for deenergizing the heater 26 and for energizing the timer motor 54. The latter then drives the cams 77 and 78.

When drying a heavy load, the heater 26 will be energized for a relatively long period of time, during which a relatively large amount of heat is stored in the fabrics and the drier structure. Accordingly, the thermostat 72 being of the wide differential type, a relatively long period of time elapses between the opening of the thermostat contacts 24 and the reclosing thereof. With a light load, the heating of the fabrics is more rapid and less heat is stored in the drier structure than when the load is heavy. Accordingly, the cooling of the thermostat is more rapid and it recloses its contacts 74 in a shorter period of time than when the load is heavy.

During operation with a heavy load, the timer operates to open the switches 81, 82 and 83 prior to the reclosing of the contacts 74 by the thermostatic element 73 because, as pointed out heretofore, the large amount of heat stored in the drier structure prevents early reclosing of the thermostatic switch 72. Accordingly, the heater 26 may be energized only once during the drying cycle.

When the load is light, more rapid heating and cooling of the drier structure may effect operation of the heater and timer several times during a drying cycle. As described in connection with the prior embodiment, the manual advancing of the timer knob 55 beyond the "on" position will shorten the total period of the drying cycle. Accordingly, variable amounts of dampness in the fabrics at the end of the cycle may be selectively obtained by the proper adjustment of the knob.

From the foregoing description, it will be apparent that I have provided improved drying apparatus wherein the material being treated is dried and then cooled for handling, a substantial portion of the heat remaining in the material and the drier structure subsequent to terminating operation of the heater being utilized to complete the drying operation. The various steps in the drying cycle are automatically effected by a master control or timer which may be adjusted to vary the degree of drying, the desired degree being obtained regardless of the weight of the load being dried. This operation is obtained automatically by varying the duration of the period of time that the heating means is conditioned for operation in response to the load on the drying apparatus. The cooling step in the cycle is carried out during a fixed period of time.

What I claim is:

1. In drying apparatus, the combination of means defining a drying chamber for the material to be dried, means for circulating air through said chamber, means for heating the air, control means for the air heating and air circulating means adjustable from an inactive position to an active position for initiating operation of the air circulating means and the heating means, a timer for actuating the control means to its inactive position, said control means being effective to terminate operation of the heating means after a predetermined period of operation of the timer and to terminate operation of the air circulating means after a second longer period of operation of the timer, means responsive to a predetermined low temperature of the heated air for energizing the heating means and responsive to a predetermined high temperature of the heated air for deenergizing the heating means during periods of operation of the latter, and means responsive to predetermined low and high temperatures of the heated air for, respectively, terminating and initiating operation of the timer.

2. The combination as claimed in claim 1, including means rendered effective after a predetermined period of operation of the timer for operating said timer independently of the temperature-responsive means.

3. The combination as claimed in claim 1, including manually-actuated means movable at will for terminating operation of the timer during periods when the control means is adjusted to its active positions.

4. In a drier, the combination of means defining a chamber for material to be dried, electrically-operated means for circulating air through said chamber, electric heating means for heating said air, first and second switches controlling energization of said air circulating means and said air heating means, respectively, means for closing said first and second switches when initiating a drying cycle, thermostatic means controlling energization of said heating means, said thermostatic means effecting the energization of the heating means in response to a predetermined low temperature of said air and deenergization of the heating means in response to a predetermined high temperature of said air, motor-driven timing means for actuating said second switch to its open position after a predetermined period of operation of the timing means and actuating the first switch to its open position after a predetermined, longer period of operation of the timing means, means actuated

75 by said thermostatic means for energizing the

timing means during periods when the heating means is deenergized and for deenergizing the timing means during periods when the heating means is energized, and switch means for energizing the timing means independently of the thermostatic means after a predetermined period of operation of the timing means, said switch means being effective to deenergize the timing means at the conclusion of the drying cycle.

5. The combination as claimed in claim 4, including a manually-actuated switch controlling energization of the timing means and movable, at will, to an open position for terminating operation of the timing means.

6. In drying apparatus, the combination of means, defining a drying chamber for the material to be dried, means for circulating air through said chamber, means for heating the air, first and second switching means respectively controlling operation of the air circulating and the air heating means, motor driven timing means actuating the first and second switching means for cycling the air heating and air circulating means in a predetermined program, a thermostat movable to first and second positions in response, respectively, to predetermined high and low temperatures of the circulated air, a switch actuated

5 by said thermostat and connected in series with said second switching means, said switch being open and closed, respectively, in said first and second positions of the thermostat, and a second switch actuated by said thermostat and connected in series with said motor driven timing means, said second switch being closed and open, respectively, in said first and second positions of the thermostat.

10 7. The combination as claimed in claim 6, including third switching means actuated by said motor driven timing means and connected in parallel with said second switch.
